UNITED STATES PATENT OFFICE

2,073,546

PARING KNIFE

Thomas V. Baker, Chehalis, Wash.

Application June 15, 1936, Serial No. 85,377

7 Claims. (Cl. 30—20)

My invention relates to improvements in paring knives for vegetables, fruit or the like and is designed as an improvement over my co-pending application, Serial No. 85,378 filed June 15, 1936.

5 In my co-pending application a pair of knife blades are secured to a handle for the setting of one relative to the other to predetermine the thickness of the parings to be cut and relatively arranged particularly for opposite manipulation 10 or wielding by right and left handed individuals. The cutting blades are separate members and the settable one is slidably mounted in a separate socket on the handle for screw adjustment to different set positions.

15 My present invention is designed to provide a pair of cutting blades relatively settable in a manner similar to that described in said application, and for the same purpose, but formed as a single piece structure adapted for flexing to effect the 20 setting of the one blade.

25 My present invention furthermore comprehends effecting such setting of the one blade by lever operation together with other improvements such as elimination of the separate socket of my former application, all for the purpose of effecting economy in manufacture of the knife without impairing its efficiency.

The precise nature of my improvements will be more clearly understood when the following 30 description and claims are read with reference to the accompanying drawing.

Figure 1 is a view in top plan of my improved paring knife.

Figure 2 is a view in longitudinal section taken 35 on the line 2—2 of Figure 1 looking in the direction indicated by the arrows.

Figure 3 is a view in front end elevation illustrating the knife set for use by a right handed person and drawn to an enlarged scale, and,

40 Figure 4 is a similar view illustrating the knife adjusted for use by a left handed person.

45 Referring to the drawing by reference numerals, my paring knife, according to my present invention, comprises a handle 1 preferably cylindrical, and formed of wood, and provided with a reduced front end portion 2 forming a shoulder 3 around said handle 1 spaced from the front end thereof.

50 The cutting parts proper are formed as a single piece structure comprising a cylindrical ferrule 4, formed of any metal suitable for cutting purposes, preferably somewhat resilient, and having a rear end portion fitting over the reduced portion 2 of the handle 1 against the shoulder 3

and a front end portion 4' extending forwardly of said handle.

The rear end of the ferrule 4 is secured to the reduced portion 2 by a pin 5 passing through said ferrule and portion and upset at its ends. A pair 5 of parallel cutting blades 6 and 7 respectively, transversely arcuate and double edged, extend forwardly from the front and bottom edge of the ferrule 4 in side by side, spaced apart, relation upon opposite sides of the longitudinal center of 10 the handle 1 respectively. In this position the blades provide inner bottom cutting edges 8 thereon opposed to each other and upper outer cutting edges 9. The ferrule 4 is longitudinally split at its bottom throughout its extended portion 4' as indicated at 10, and transversely split, as indicated at 11 adjacent to the front end of the handle 1 to intersect the longitudinal split and to provide a free portion 12 carrying the 15 knife blade 7. As will be clear the free portion 12 together with the knife blade 7 are thereby 20 adapted for movement bodily with respect to the relatively fixed knife blade 6. The knife blade 7 is moved to different set positions in a general 25 direction at a right angle to the cutting plane of the stationary blade 6 to predetermine the thickness of the paring to be cut and by the following means:

20 The longitudinally split edges of the extending part 4' of the ferrule 4 are coupled together by 30 means of a straight link 13 mounted upon said edges to extend along the same and provided at its front end with a right angularly disposed lever 14 extending between the blades 6 and 7 across the outer end of the ferrule 4 and projecting 35 slightly beyond the top of same. The lever 14 is preferably extended between the blades 6 and 7 through a notch 15 provided in said ferrule in the rear of the cutting edges 8 and 9. The arrangement of the link 13 is such that it has a fulcruming action on the ferrule part of the stationary blade 6 under movement of the lever 14 40 in opposite directions from a central position to thereby flex the free or movable part 12 of the ferrule, and hence the blade 7. The flexing movement is substantially diametrically of the handle 45 in opposite directions respectively and in the direction relative to the cutting edge of the blade 6 previously specified.

50 The handle 14 is held in different set positions by means of a detent lug 16 thereon engaging teeth 17 formed on the front end edge of the ferrule 4. The lever 14 is adapted to be flexed outwardly to disengage the detent lug 16 from 55

the notches 17 and to spring inwardly when released to engage said lug and notches. The split 10 in the ferrule 4 may extend clear through the same to separate the ferrule at its rear end, as indicated at 10' so that said ferrule may be fitted over the reduced portion 2 with a clamping action by spreading such separate ends apart.

By setting the lever 14 in one direction from a central position the movable blade 7 is correspondingly set as shown in Figure 3 so that when the knife is used by a right handed person the fixed cutting blade 6 performs the cutting operation and the movable or settable blade 7 acts as a gage bar riding over the article being pared to determine the depth of the cut and hence the thickness of the paring. By setting the lever 14 in the opposite direction the movable blade 7 is set to perform the paring operation and the fixed blade 6 to perform the gaging operation as shown in Figure 4 so that the knife under such setting may be wielded by a left-handed person. The top cutting edges 9 may be used for any purpose such as trimming or the like. The front ends of the blades 6 and 7 are sharpened to cutting edges 18 for use in any desired matter.

It is believed that the foregoing description of my invention will suffice to impart a clear understanding thereof.

It is to be understood that the details described are illustrative of the principles of the invention rather than restrictive and that right is herein reserved to modifications of such details falling within the scope of the claims appended hereto.

What I claim is:

- 35 1. A paring knife comprising, a handle, a ferrule of resilient metal mounted on one end of said handle and having formed integrally therewith a pair of parallel cutting blades extending forwardly of said ferrule in side by side latterly spaced relation, said ferrule being split to provide a free flexing portion carrying one of said blades, and manipulative means for flexing said portion.
- 45 2. A paring knife comprising, a handle, a ferrule of resilient metal secured to one end of said handle to extend beyond the same and having formed integrally therewith a pair of parallel cutting blades extending forwardly thereof in side by side latterly spaced relation, said ferrule being longitudinally and transversely split beyond said end of the handle to provide a free flexing portion carrying one of said blades, and manipulative means for flexing said portion to different set positions.
- 55 3. A paring knife comprising, a handle, a ferrule of resilient metal mounted on one end of said handle to extend beyond the same and having formed integrally therewith a pair of parallel cutting blades extending forwardly thereof in side by side latterly spaced relation, said ferrule being longitudinally split beyond said end of the handle and intermediate said blades to provide a free flexing portion carrying one of said blades, and manipulative means for flexing said portion into different positions.
- 65 4. A paring knife comprising, a handle a fer-

rule of resilient metal mounted on one end of said handle to extend beyond the same and having formed integrally therewith a pair of parallel cutting blades extending forwardly thereof in side by side latterly spaced relation, said ferrule being longitudinally split beyond said end of the handle and intermediate said blades to provide a free flexing portion carrying one of said blades, and manipulative means for flexing said portion into different positions and comprising a rocking member fulcrumed on said ferrule and embracing one edge of said free portion, and a lever for rocking said member.

5 5. A paring knife comprising, a handle, a ferrule of resilient metal mounted on one end of said handle to extend beyond the same and having formed integrally therewith a pair of parallel cutting blades extending forwardly thereof in side by side latterly spaced relation, said ferrule being longitudinally split beyond said end of the handle and intermediate said blades to provide a free flexing portion carrying one of said blades, and manipulative means for flexing said portion into different positions comprising a rocking member fulcrumed on said ferrule and embracing one edge of said free portion, and a lever for rocking said member.

10 6. A paring knife comprising, a handle, a ferrule of resilient metal mounted on one end of said handle to extend forwardly of the same and having formed integrally therewith a pair of parallel cutting blades extending forwardly thereof in side by side latterly spaced relation, said ferrule being longitudinally and transversely split beyond said end of the handle to provide a free flexing portion carrying one of said blades, and manipulative means for flexing said portion comprising, a link fulcrumed upon the opposed edges of said ferrule contiguous the longitudinal split thereof and extending beyond the front end of the ferrule and terminating in a right angularly disposed lever extending across and beyond the front end of the ferrule.

15 7. A paring knife comprising, a handle, a ferrule of resilient metal mounted on one end of said handle to extend forwardly of the same and having formed integrally therewith a pair of parallel cutting blades extending forwardly thereof in side by side latterly spaced relation, said ferrule being longitudinally and transversely split beyond said end of the handle to provide a free flexing portion carrying one of said blades, and manipulative means for flexing said portion comprising, a link fulcrumed upon the opposed edges of said ferrule contiguous the longitudinal split thereof and extending beyond the front end of the ferrule and terminating in a right angularly disposed lever extending across the front end of the ferrule, said lever and front end of ferrule being provided with tooth and notch device, respectively, for interlocking the lever with said ferrule in different positions of said lever.
